CLAIM

The ornamental design for a mini pocket hole jig tail spacer, as shown and described.

DESCRIPTION

FIG. 1 is a top elevational view of a mini pocket hole jig spacer;

FIG. 2 is a bottom elevational view of a mini pocket hole jig spacer;

FIG. 3 is a rear elevational view of a mini pocket hole jig spacer;

FIG. 4 is a front elevational view of a mini pocket hole jig spacer;

FIG. 5 is a side elevational view of a mini pocket hole jig spacer;

FIG. 6 is another side elevational view of a mini pocket hole jig spacer;

FIG. 7 is a top rear perspective view of a mini pocket hole jig spacer;

FIG. 8 is another top rear perspective view of a mini pocket hole jig spacer;

FIG. 9 is a top front perspective view of a mini pocket hole jig spacer;

FIG. 10 is another top front perspective view of a mini pocket hole jig spacer;

FIG. 11 is a bottom rear perspective view of a mini pocket hole jig spacer;

FIG. 12 is another bottom rear perspective view of a mini pocket hole jig spacer;

FIG. 13 is a bottom front perspective view of a mini pocket hole jig spacer;

FIG. 14 is another bottom front perspective view of a mini pocket hole jig spacer;

FIG. 15 is a top elevational view of a mini pocket hole jig spacer, shown in connection with mini pocket hole jigs and their respective, attached tail sections, as shown in dashed lines for intended use purposes;

FIG. 16 is a bottom elevational view of a mini pocket hole jig spacer, shown in connection with mini pocket hole jigs and their respective, attached tail sections, as shown in dashed lines for intended use purposes;

FIG. 17 is a rear elevational view of a mini pocket hole jig spacer, shown in connection with mini pocket hole jigs and their respective, attached tail sections, as shown in dashed lines for intended use purposes;

FIG. 18 is a front elevational view of a mini pocket hole jig spacer, shown in connection with mini pocket hole jigs and their respective, attached tail sections, as shown in dashed lines for intended use purposes;

FIG. 19 is a top rear perspective view of a mini pocket hole jig tail spacer, shown in connection with mini pocket hole jigs and their respective, attached tail sections, as shown in dashed lines for intended use purposes;

FIG. 20 is another top rear perspective view of a mini pocket hole jig tail spacer, shown in connection with mini pocket hole jigs and their respective, attached tail sections, as shown in dashed lines for intended use purposes;

FIG. 21 is a bottom rear perspective view of a mini pocket hole jig tail spacer, shown in connection with mini pocket hole jigs and their respective, attached tail sections, as shown in dashed lines for intended use purposes;

FIG. 22 is a top front perspective view of a mini pocket hole jig tail spacer, shown in connection with mini pocket hole jigs and their respective, attached tail sections, as shown in dashed lines for intended use purposes;

FIG. 23 is another top front perspective view of a mini pocket hole jig tail spacer, shown in connection with mini pocket hole jigs and their respective, attached tail sections, as shown in dashed lines for intended use purposes; and,

FIG. 24 is a top rear exploded perspective view of a mini pocket hole jig tail spacer, shown in connection with mini pocket hole jigs and their respective, attached tail sections, as shown in dashed lines for intended use purposes.

The broken lines in the drawings illustrate environmental structures of multiple mini pocket hole jigs, tail section attachments, and portions of the mini pocket hole jig tail spacer that form no part of the claimed design.
